BLANCHING MACHINE

Dallas B. Benham, Minneapolis, Minn.

Application December 7, 1931, Serial No. 579,488

11 Claims. (Cl. 146—32)

This invention relates to improvements in blanching machines. Such machines are used for removing the skins or husks from various kinds of nuts, either whole nuts, or those like peanuts which are split along a natural cleavage line into halves. The main objections to the existing commercial machines are that: husking is not thoroughly accomplished, even by repeated running of the material through a series of machines; many of the nuts are crushed or put in condition which prevents the sorting operation usually performed after blanching, with a resultant comparatively large loss of material; the operation is comparatively slow; the machines are expensive to repair; and their use is expensive in that a plurality of machines operated in sequence are required, and the nuts must be run through these machines more than once to obtain proper blanching. By the practice of this invention, these objections are substantially overcome.

Features of the invention include the use of cushion material for the working face of one of the blanching elements; the use of a comparatively stiff but flexible covering for this compressible cushion base; the use of a rotative or oscillative element in cooperation with the aforesaid element to assist in the control of speed and direction of the material, so that the entire surface of each nut is acted upon, whether regular or irregular; the provision of means for adjusting the spacing between the elements; the delivery of the material centrally of the elements and creation of a suction which removes the husks at a point peripherally thereof; and generally all details of construction as well as the broader ideas of means inherent in the general disclosure.

Objects, features and advantages of the invention will be set forth in the description of the drawings forming a part of this application, and in said drawings

Figure 1 is a sectional elevation illustrating one embodiment of the invention;

Figure 2 is an enlarged detail of the adjusting means of one of the blanching elements;

Figure 3 is a plan section, taken substantially on line 3—3 of Figure 1;

Figure 4 is a plan of the cushioned blanching element, viewed as approximately indicated by line 4—4 of Figure 1;

Figure 5 is a radial section through the cushioned blanching element, taken on line 5—5 of Figure 4; and

Figure 6 is an edge view of one of the corrugated plates of one of the blanching elements.

Referring first to Figure 1: Numerals 1 indicate

suitable legs which support a table 2. Upon this table is supported a motor 3, and a gear box 4. The motor shaft is indicated at 5 and has thereon a suitable worm gear 6, and companion gear 7, shown in dotted lines in Figure 3. A fan shaft 8 extension from the gear is indicated at 8. The fan has not been indicated but the casing is indicated at 9. The support for the fan casing is not shown. The fan represents any ordinary type of suction device. The exhaust is indicated at 10 and the intake at 11. This fan is for the purpose of creating a suction to separate husks from the blanched nuts. The drive shaft for the blancher elements is indicated at 15, and has a splined connection as at 16 with the gear 7 to permit it to be vertically adjusted. Any suitable gearing may be employed for changing the speed ratios according to the character of the work in hand.

The numeral 20 indicates the blancher casing which is suitably supported by pedestals 21 (only one shown) in turn supported by table 2. Centrally of this casing and extending below it is a vertical tubular bearing 22 for the shaft 15. The bearing is exteriorly threaded as at 23. Referring to Figure 2, the shaft 15 has secured thereto for rotation therewith, one element 25 of a ball bearing, the other element of which is indicated at 26 and the balls of which are indicated at 27. This bearing may be of any preferred form, but at least the lower surface of its outer element is in frictional contact with the upper surface of a tubular shaft support 28 in adjustable threaded engagement with the threads 23. A lock nut 29 engages the top edge of the bearing support 28 to secure it against rotation after adjustment. The splined connection of the shaft 15 with gear 7 permits axial adjustment, while maintaining the driving connection.

Attached for rotation with the shaft at its upper end is a plate 30 which forms one of the blanching elements. This disk has a depending hub 31 which telescopically engages a tubular extension 32 of the box 20. By manipulating the element 28 (in this embodiment vertically), the shaft can be lowered or raised to correspondingly lower or raise the disk for varying the spacing between the working faces of the blancher elements. Attached to the top of the disk 30 (see Figures 3 and 6) are a series of plates indicated by the numeral 35. Each plate is provided with parallel ribs or corrugations 36. One side or edge 37 of each plate is radial with respect to the axis of the shaft 15, but since the ribs are parallel with that side, they are tangent with

respect to a series of imaginary circles having their centers in the axis of shaft 15. This is a feature of the invention, although there is no intention to limit the broader aspects to the particular character of the roughened working surface of the element 30. It will also be understood that these grooves may be cast as a part of the disk, but they are herein removably attached so that others may be substituted for them when they are sufficiently worn. However, the function of the grooves is to prevent straight radial travel, as well as to prevent a too rapid travel of the nuts toward the periphery of the disk. As shown in Figure 1, the periphery of the disk is very closely spaced with reference to the vertical inner wall of the casing 20, so that the nuts can only escape at the discharge point, and after thorough blanching.

Referring to Figure 3, the nuts, after blanching, are delivered horizontally through an opening 39 in the casing 20, and into a horizontal conduit 40 having upper and lower vertical communicating colinear extensions 42-43 which are respectively connected to suitable piping 44-45. The upper extension 44 may connect with a cyclonic separator (not shown). The husks are drawn off by means of suction created by the fan. There are other ways in which the husks can be disposed of, and the particular arrangement with the exception of the elements 40, 42 and 43 is optional. The broad idea is to manipulate or control the material after separation so as to create sufficient suction to cause separation between the huskings and the blanched nuts. It will be understood that it is principally the mechanical action of the blanching elements which is responsible for the feeding of the nuts toward the discharge point.

A very important feature of the invention relates to the construction of the second blanching element which is herein shown as attached to a cover 50 of the box 20. Placed against the lower side of this cover is a layer or bed 52 of rubber. This bed is of annular configuration and is provided with a series of downwardly directed nipple-like projections 53, see Figure 4, which are suitably spaced. The stiffness, dimensions and spacing of these projections are varied in accordance with the character, form and condition of the article which is being handled. After adjustment of the plate 30, the machine can properly blanch nuts which vary considerably in size. However, the projections ordinarily do not act directly on the nuts but are covered and bridged by a piece of canvas 54 suitably marginally secured by ring 55 to the cover 50 at the outer periphery. At the inner periphery, the canvas is secured by a clamping element 60 which has a vertical tubular extension 61 whose axis is co-linear with the axis of rotation of the shaft 15 which extends outwardly through the cover 50. This tubular extension 61 is threaded as at 62 and a nut 63 applied at the outer side of the cover 50 as shown acts to draw the element 60 to clamp the canvas in operative position. A suitable hopper 66 has its lower tubular end 67 telescopically engaged in the element 61.

The cover 50 is held in position by gravity. Its weight, in the present embodiment, is about seventy pounds. It is free to rise in case of unusual obstructions, and thus acts to protect the blancher elements against injury. Suitable handles 69 are provided for lifting the cover. In the preferred embodiment of the invention, the cushion blanching element, including the parts 52 and

54 are attached to the cover so that a vertical feed can be had through the top of the device from the hopper as shown. This cushion element 52 may, however, be carried by the element 30 and the elements 35 may be attached to the cover. It will be noted that the cover merely rests by gravity and if any clogging or undue strain occurs, relief is immediately had. Moreover, it is very convenient to remove the cover for inspection purposes.

One of the salient features of the invention is the use of compressible elastic material like rubber over which is spread a canvas or equivalent flexible non-elastic fabric, and this is a feature of the invention irrespective of the use of the projections 53. However, the use of the nipples is a very valuable feature, either alone or in combination with the particular arrangement of the ribs 36.

The nipples yield or are pressed or swung laterally against their resiliency as the result of pressure transmitted through or by the fabric, by those portions of the fabric which bridge the nipples. This tends to crowd two or more of the nipples in opposite directions producing a shallow irregular channel or rut, as a guide for the nuts causing them to be rotated and oscillated, so that the entire surface is submitted to friction. The nuts are moved by frictional, rotative, and oscillatory action across the faces of the blanching elements in a tortuous course and are frictionally rubbed and completely rotated as well as given frictional strokes simultaneously from opposite sides so that each nut is manipulated generally in the manner as when rolled and stroked between the forefinger and thumb of the hand.

The disk is ordinarily rotated about one hundred and seventy-five revolutions per minute. The action of the suction fan removes the husks which may be carried to cyclone separators, not shown, in which the husks and ground matter are drawn to the outside while the blanched nuts are centrally collected and packed.

It will be understood that there is no intention to limit the device to the blanching of any particular kind of nut. The most valuable application is for blanching split peanuts, but the machine is adjustable to operate on whole almonds, or peanuts and on various other nuts which have husks.

When the machine is used for blanching peanuts, the shelled and split nuts are first roasted, and then they are run from the roaster into the blancher. After blanching, the nuts are picked to remove the objectionable portion.

In some of the old machines, triangular shaped brushes are used, fastened on a plate which is rotatable, the brushes being arranged on the plate as triangular segments with their apices faced toward the center of rotation. This type of machine is quite objectionable because the brushes soon become clogged with the oily meal and with the husks so that the brushes slide over the nuts without removing the husks. Moreover, the brushes lose their stiffness and it is necessary to replace them about every two weeks at a cost of anywhere from ten to twenty dollars for each disk. Replacement of the canvas used herein costs about forty cents. Moreover, in certain older types of machine, the brushes rotate on a horizontal axis (working faces vertically disposed) and the brush and plate surfaces are not arranged in parallel relation but are arranged in downwardly flared relation so that a very small area of the brush is actually used, instead of the

entire available surface or area, as in the present device.

In the present device, the entire surface of both of the blanching or husking surfaces are available, and are used and the nipple-like projections of the cushion surface act to give a tortuous course to the nuts, which simulates an action of rolling, pressing and stripping the nut between the index finger and thumb of the hand.

10 When brushes are used, the nuts in which the parchment or husk is more adherent are likely, because of the greater degree of give or flexibility of the brushes, to pass through the machine without being blanched. It, therefore, results 15 that in this case, the nuts must be run through the machine more than once. By the use of this device, as distinguished from those having brushes, the amount of hand picking is reduced because the smaller sized and more irregular 20 shaped nuts are acted upon.

By "compressible elastic material" is meant a material like rubber which will resume its original shape after deformation.

In the present instance, the annulus of elastic 25 compressible material with its nipples is formed from rubber by molding. However, these nipples may be separately formed and they may be applied to a hard base and may alone form the compressible elastic material; or they may be made 30 of stiff material, and be so mounted as to yield laterally and/or axially. The invention also contemplates the use of nipples or projections which are bridged by the fabric, and which are capable of movement beneath the fabric whether these 35 nipples be of elastic compressible material or whether they be so attached as to swing laterally from their points of attachment. Although the compressibility is a very valuable feature, any arrangement by which the fabric can be pushed upwardly between these nipple-like projections is broadly claimed. In this case, the fabric is sufficiently flexible as to be pushed between the nipples by the nuts, sufficient pressure being applied by properly adjusting the shaft 15. Under these 45 conditions, the nuts cannot be caught or broken by the projections but the projections act to give the nut a tortuous course.

Separate claimed features are: the use in a blanching machine, of compressible elastic material with or without nipples; the use of elastic material with or without fabric covering; the construction of a working face of fabric over compressible elastic material; the use of fabric which bridges nipples of any material mounted on any 55 kind of a base; the use of a non-radial surfaced element in conjunction with any one, or with any combination of the above mentioned features; the feeding of the material centrally of the blanching elements; the utilization of a fabric clamping element as a passage for introducing the material 60 into the blanching zone; the horizontal arrangement of the blanching elements; the utilization of a common shaft for driving the rotatable blancher element and fan; the utilization of the lid as a support for one of the blanching elements; the mounting of one of the blanching elements on the cover for the blanching chamber; the utilization of the gravity action of the lid as a 65 safety device; the means for adjusting the shaft of a rotatable blancher element; and generally the constructional details disclosed, and suggested.

The plates 35 may be designated "lead" plates. They function to lead the nuts in a definite direction, and thus force them always to move out-

wardly toward the periphery of the disk. These plates also hasten the action or motion by preventing "milling".

Another advantage which the present structure has over certain of the older types of machines, is that there is no possibility of transfer of lubricating oil from the shaft bearings to the nuts. In some types of machine, the drive shaft traverses the grinding chamber, and the nuts are so fed that they come into contact with the shaft. Inasmuch as the oil escapes along the shaft, the nuts pick it up as they contact the shaft on their way to or even after entry into the grinding chamber. Moreover, when the brush type of machine is operating on nuts which are particularly hard to blanch, the brush pressure cannot be made great enough because of the flexibility of the brush material and, therefore, the blanching is not complete. In the present device, proper pressure can always be applied by adjusting the shaft 15 axially to bring the surfaces of the elements 35 and 54 closer together. The brushes of these old machines are bent in such manner that the nuts are "bunched" so that many go through without being touched. With the present machine, bunching and over-load are impossible owing to the comparative rigidity of two blanching surfaces.

I claim as my invention:

1. A blanching machine having blanching elements having opposingly faced working surfaces between which the material to be blanched is fed, means for moving one of the elements relative to the other, one of the elements having nipple-like projections, and fabric covering and bridging said projections and acting as a working surface which can be depressed at points between the projections.

2. A blanching machine having blanching elements having opposingly spaced working surfaces between which the material to be blanched is fed, means for moving one of the elements relative to the other, one of the elements having separate projections pointing toward the working face of the opposite element and laterally yieldable in any direction, said fabric covering and bridging said projections.

3. A blanching machine having blanching elements having opposingly spaced working surfaces between which the material to be blanched is fed, means for moving one of the elements relative to the other, one of the elements including a base of compressible elastic material covered by flexible non-elastic fabric, said compressible material having series of nipple-like projections of the same material which are engaged and bridged by the fabric.

4. A blanching machine having blanching elements having opposingly spaced working surfaces between which the material to be blanched is fed, means for moving one of the elements relative to the other, one of the elements including a base of compressible elastic material covered by fabric, and tubular clamping means passing through and securing the fabric to said compressible base in operative position, said tubular means being so arranged that material can be introduced through it to a point between the blanching elements.

5. A blanching machine having blanching elements having opposingly faced working surfaces between which the material to be blanched is fed, means for moving one of the elements relative to the other, one of the elements including nipple-like projections and said projections

- being covered and bridged by fabric, one of said elements being rotatable and having a working face formed by plural series of corrugations which are substantially non-radial to the rotative axis of the element.
6. A blanching machine having blanching elements having opposingly faced working surfaces between which the material to be blanched is fed, means for moving one of the elements relative to the other, one of the elements including nipple-like projections and said projections being covered and bridged by fabric which forms its working face, one of said elements being rotatable and having a working face formed by a plurality of series of parallel corrugations, substantially only one corrugation of each series being radial to the axis of rotation, and the others being tangent to imaginary circles which have their centers in the rotative axis of the element.
7. A blanching machine having blanching elements having opposingly spaced surfaces between which the material to be blanched is fed, means for moving one of the elements relative to the other, one of the elements including an annular base of compressible elastic material, covered by canvas, said material having a series of nipple-like projections of the same material which are engaged and bridged by the fabric.
8. A peanut blanching machine having blanching elements having opposingly faced working surfaces between which the material to be blanched is fed, one of the elements having nipple-like projections formed of rubber and pointing toward the working face of the other element and a single piece of fabric stretched across and bridging the free ends of the nipples, said nipp-
- les being spaced apart a distance less than the average width of the nut to be blanched.
9. A blanching machine having blanching elements having opposingly faced working faces between which the material to be blanched is fed, one of the elements comprising a solid base of compressible elastic material having integral nipples, said nipples pointing toward the working face of the opposite elements, and a single piece of fabric contacting and bridging the nipples.
10. A blanching machine having blanching elements having opposingly faced working surfaces between which the material to be blanched is fed, the upper element including an annular base of compressible elastic material covered by fabric, the outer surface of which engages the peanuts, a tubular member passing through the top of the machine and traversing the annular base and having a flange clampingly engaging and operatively securing the inner periphery of the fabric, said tubular member constituting a feed passage by which the material is delivered between the opposingly spaced blanching elements.
11. A blanching machine having blanching elements having opposingly faced working surfaces between which the material to be blanched is fed, one of said elements comprising spaced nipples pointing toward the other blanching element, and a single piece of fabric bridging the ends of said nipples and being sufficiently loose to allow the nuts to be pressed between the nipples and means for adjusting one of the blanching elements relative to the other, to apply sufficient pressure to the nuts to cause them to deflect the fabric between the nipples.
